LEON WYGODSKY, OF BALTIMORE, MARYLAND, ASSIGNEE TO BALTIMORE OIL ENGINE COMPANY, OF BALTIMORE, MARYLAND, A CORPORATION OF DELAWARE.

INTERNAL-COMBUSTION ENGINE.

1,312,605.

Specification of Letters Patent. Patented Aug. 12, 1919.

Original application filed August 22, 1917, Serial No. 187,662. Divided and this application filed November 23, 1918. Serial No. 263,854.

To all whom it may concern:

Be it known that I, LEON WYGODSKY, a citizen of the United States, and a resident of Baltimore city, in the State of Maryland, have invented certain new and useful Improvements in Internal-Combusion Engines, of which the following is a specification.

My invention relates to improvements in internal combustion engines, particularly multi-cylinder engines, wherein there is a compression space between pistons moving, in general, in opposite directions relatively. I have illustrated and described my invention, herein, in connection with an engine of my invention set forth in my application for Letters Patent, Serial No. 187,662, filed August 22, 1917. In that engine, there are two crank shafts and means is required for transferring power from the one crank shaft to the other. In that engine also air for combustion and for scavenging purposes is supplied to the compression spaces between the several pairs of coacting pistons, by so-called scavenging pumps driven by the engine; and it has been found convenient to combine this pump mechanism with the mechanism for transferring power from one crank shaft to the other.

My invention consists in the novel mechanism herein illustrated, described, and claimed for transferring power from the one crank shaft to the other; in the novel arrangement of pump mechanism mentioned with respect to such power transferring mechanism; and in various other features hereinafter described and particularly pointed out in the appended claims.

The object of my invention is to improve internal combustion engines, particularly engines of that type wherein there are two crank shafts which are to be driven in substantial synchronism, and also particularly that type wherein one or more scavenging pumps or other air pumps are to be driven by the engine.

I will now proceed to describe my invention with reference to the accompanying drawings, and will then point out the novel features in claims. In said drawings:

Figure 1 shows a transverse vertical section of the engine, through the center of one of the cylinder structures; Fig. 2 shows a partial side view and partial oblique section on the line 2-2 of Fig. 1. Fig. 3 shows an

end elevation and partial central vertical section of the mechanism for transmitting motion from the upper to the lower crank shaft and of two of the scavenging pump cylinders, one of which cylinders is shown in central vertical section on the line 3-3 of Fig. 4; Fig. 4 shows a horizontal section of the scavenging pump on the irregular section line 4-4 of Fig. 3. Fig. 5 shows a central vertical section through one of the cylinders and valve chambers of the scavenging pump, the section being taken on the line 5-5 of Fig. 4; Fig. 6 is a side elevation of one of the valve cages of Fig. 5, with portions of the valve bands broken away; Fig. 7 is a top view and partial horizontal section of the valve structure shown in Fig. 6.

In the drawings: 1 designates the engine frame; 2 designates a combustion-chamber and working-cylinder structure, to which are attached guide cylinders 3. 4 designates the engine pistons, 5 designates a lower crank shaft, and 5' an upper crank shaft, power being transmitted from one crank shaft to the other by mechanism hereinafter described. 6, 6 designate jacketed air-inlet manifolds, to which air is supplied by the scavenging pumps as hereinafter described, and from which air passes, at suitable times, to a belt of inlet ports 7, for each cylinder structure 2, uncovered by the upper piston 4 of that structure when that piston nears the outboard or upper end of its stroke. 8 designates a jacketed exhaust manifold, to which exhaust gases pass from a port belt 9, for each cylinder structure 2, which port belt 9 is uncovered by the lower piston 4 of that structure when such piston nears the lower or outboard end of its stroke. 10 and 11 are the cylinders proper, located within the cylinder structure 2, with their axes angularly related relatively. This engine is designed to work at a compression pressure of approximately 300 pounds to the square inch, and, therefore, a small clearance space is necessary when the two pistons 4 are at the inboard limits of their stroke. The piston heads are provided with curved surfaces, 15, when the two pistons are at the inboard ends of the stroke, there will be a clearance space, in which air, compressed by the rearward motion of the pistons, will lie, and into which oil may be sprayed by a suitable sprayer set into the port 17.

In order to reduce the clearance space to obtain the desired compression pressure, part of each piston is cut away, so as to provide plane oblique surfaces 12, 13, as clearly shown in Fig. 1.

The port belts 7 and 9 are formed, in the guide cylinders 3, as slots separated by port-bridges, which slots are open at the inboard ends of the guide cylinders 3, so far as those cylinders are concerned, but are closed by the proximate surfaces of the cylinder structure 2. These guide cylinders 3 are bolted to the cylinder structure 2. The general structure is such as to provide a clear flow 15 for air into, and clear flow for exhaust gases out of, the cylinders, when the ports are uncovered by the corresponding pistons. Owing to the fact that the exhaust is from the ports at the bottom of the cylinder structure 20 2, any liquid or solid deposits in the cylinder structure will be swept out of the exhaust ports by the exhaust gases and by air entering the admission ports. The pistons are connected to the cranks of the crank shafts 25 5 and 5^a by the usual connecting rods 18 and 19. As shown particularly in Fig. 3, one of the connecting rods working on each crank pin is forked, the connecting rod of the laterally opposite cylinder working on that 30 same crank pin, and having its end lying within the fork of the other connecting rod working on that crank pin. Assuming, for the moment, the supply of air under pressure from scavenging pumps, to be mentioned 35 hereinafter, to the inlet manifolds 6, and assuming, for the present, the transmission of power by means hereinafter described, from one crank shaft to the other, the operation of the engine is as follows:

In Fig. 1, the pistons 4 of the lefthand side of the engine are shown in such position that the air inlet ports and the exhaust ports are open. Air for scavenging purposes, and for the supporting of combustion 45 during the next ensuing power stroke, is, therefore, passing from manifolds 6 through the air admission ports 7, and is also sweeping exhaust gases of the previous power stroke out through the exhaust ports 9 and 50 exhaust manifold 8. Immediately after the beginning of the inboard strokes of the pistons 4, the ports 7 and 9 are closed by said pistons, and each pair of coacting pistons then compresses the air within the cylinder 55 structure, until, finally, the pistons reach the extreme inboard position indicated in dotted lines in Fig. 1. At or about this time oil is injected through the sprayers into the compression space between the pistons, ignition taking place either due to the high temperature 60 of the walls of this space, or by reason of the oil spray being ignited by suitable igniters, not shown. The pistons then move apart, under the influence of the pressure 65 due to the ignition of the charge, and when,

near the outboard ends of the strokes of the pistons, ports 7 and 9 are uncovered, exhaust and air admission occur, the air sweeping the exhaust products out of the cylinder structure, as previously described. The lateral thrusts produced by these pistons are taken by the corresponding diagonal tie rods hereinafter mentioned. Owing to the large number of cylinders in each unit of the engine, the thrust produced by any one cylinder and its corresponding piston in any direction is relatively small; a condition which facilitates operation at high relative speed. The two crank shafts revolve in opposite directions, power being transmitted from the one to the other by means hereinafter described. For the transmission of motion from shaft 5^a to 5, or vice versa, and for the maintenance of synchronous rotation of such shafts, I have provided crank shafts 5 and 5^a with corresponding crank pins 23 and 24, located 90 degrees apart, in the construction shown, and on these crank pins are mounted bearing blocks 25, arranged to slide horizontally and transversely on bearing surfaces 90 formed on I-shaped members 26, themselves mounted to reciprocate vertically between stationary guides 27 provided on the engine frame. These members 26 are hollow, and, so far as may be, of circular cross-section, 95 and within their upper and lower horizontal arms are guide-sleeves 28, connected to the sliding bearing-blocks 25 by bolts 29 themselves working in suitable slots in members 26. By means of these sleeves 28 and bolts 100 29, the bearing-blocks 25 are held to their respective guide-surfaces of the members 26.

In a general way, the structure comprising the vertically-sliding I-shaped members 26 upon which the crank-pin bearing blocks 25 slide, forms the equivalent of "parallel rods" connecting the two crank shafts 5 and 5^a; with this exception, however, that in the construction shown the direction of rotation of the two crank shafts need not be the same, 110 but may be opposite; and as a matter of fact, in the structure shown the parts are arranged for rotation of the two crank shafts 5 and 5^a in opposite directions; this being the case in order that the same crank pins 115 of the main engine may serve for connecting rods of laterally opposite cylinders, and in order that the main engine may be reversible.

It is desirable that the engine be provided 120 with air compressing means, for the supply of scavenging air to the cylinders; and it is also convenient to use the air pumps as air motors in starting and reversing the engine. Compactness and efficiency are promoted by 125 operating the air pumps by means of the I-shaped members 26; the upper and lower horizontal arms of said members being connected by piston rods 30, carrying pistons 31 working in stationary cylinders 32 secured 130

to convenient portions of the engine frame. Each of these pump cylinders 32 is "double-acting", having upper and lower admission valves 33 (Fig. 5), of a type hereinafter described, whereby, during each suction stroke, air is admitted to the appropriate side of the pump cylinder; and having also upper and lower discharge valves 34, whereby, at a suitable point in each compression stroke, 5 the air compressed is released into a receiver space 35, whence the compressed air is conducted, by a pipe 36, forming a continuation of the receiver space, to the air inlet manifold 6. There being four double-acting 10 pump cylinders, each of large capacity, operating at the speed of the main engine, the supply of air for scavenging and for cylinder charging is ample.

As indicated in the lower part of Fig. 4, 20 the receiver space of each inner valve chamber communicates with the receiver space of the corresponding outer valve chamber, and so to the air inlet manifold.

The engine will be provided with a suitable fuel supply pump supplying fuel at high pressure to the sprayers. The engine will also be provided with some means for compressing air to high pressure for starting purposes, or an auxiliary air pump may be 30 provided for that purpose; but these are usual auxiliaries of engines of this type, and I have not thought it necessary to illustrate such auxiliaries herein.

Each admission valve 33 of each pump cylinder comprises a cage 48 with circumferential ports 49 normally closed by circular spring valves 50 hereinafter referred to. The discharge valves 34 are of similar construction to the admission valves 33. These 40 admission and discharge valves 33 and 34 have the advantages of extreme simplicity and compactness of structure, as well as extremely large area of port opening, and are suitable, not only for use in the present engine, but also for use in air compressors, particularly of the "blowing engine" type, 45 and in water pumps and various other types of engines. Each such valve cage is provided with a number of peripheral slots 49 over which is located a band 50 of spring steel or other thin, highly resilient material, 50 ground on the inside to fit closely the seat surrounding the corresponding slot 49; the slots 49 being ports leading from these seats in the interior of the valve cage. The bands 55 50 are split bands; that is to say they have free ends lying beneath the heads of screws 60, which heads hold the bands in place, both preventing the ends of the bands from flying out, and preventing rotation of the bands. Headed projections 61, located at suitable intervals also help to hold the bands 50 in place.

When, because of suction created in one of 65 the pump cylinders (in the case of an ad-

mission valve) or when the pressure in the pump cylinder becomes materially greater than that in the receiver space (in the case of a discharge valve), the pressure on the inner side of one of these bands becomes 70 greater than the pressure on the opposite side, that band opens up like a hoop, permitting passage of air; and upon creation of reverse condition of pressure the bands contract, seating against their ports. Since 75 the inside faces of these bands are ground or otherwise finished to a true surface, the seating is very tight.

Valves so constructed will work with a very small pressure differential, offer very 80 little resistance, require no mechanical parts for their operation, require no lubrication, and are very easily constructed.

In another application for Letters Patent, Ser. No. 187,522, filed August 22, 1917, I 85 have claimed the valve comprising the flexible spring band, *per se*.

What I claim is:

1. An internal combustion engine comprising in combination two crank shafts 90 mounted for rotation, cylinders and pistons therefor, arranged to drive said crank shafts, and means for communicating motion from one crank shaft to the other, comprising laterally slidable bearing blocks 95 mounted on cranks of said crank shafts, and a reciprocating member connecting said bearing blocks, and provided with slides therefor.

2. An internal combustion engine comprising in combination two crank shafts mounted for rotation, cylinders and pistons therefor, arranged to drive said crank shafts, said crank shafts each having, aside from the crank pins to which the pistons of said cylinders are connected, two other crank pins, angularly spaced apart one with respect to the other, sliding bearing blocks mounted on such crank pins, and two reciprocating members, one for each such crank pin of one said shaft and for the corresponding crank pin of the other shaft, each such reciprocating member having sliding bearings for the bearing blocks of its corresponding crank pins. 110

3. An internal combustion engine comprising in combination two crank shafts mounted for rotation, cylinders and pistons therefor, arranged to drive said crank shafts, and means for communicating motion from one crank shaft to the other, comprising laterally slidable bearing blocks mounted on cranks of said crank shafts, and a reciprocating member connecting said bearing blocks, and provided with slides 120 therefor, and a scavenging pump comprising a cylinder located in proximity to said reciprocating member, and a piston within said cylinder, and provided with connections to such reciprocating member whereby said 125 130

piston is reciprocated as said member reciprocates.

4. An internal combustion engine comprising in combination two crank shafts 5 mounted for rotation, cylinders and pistons therefor, arranged to drive said crank shafts, said crank shafts each having, aside from the crank pins to which the pistons of said cylinders are connected, two other 10 crank pins, angularly spaced apart, one with respect to the other, sliding bearing blocks mounted on such crank pins, and two reciprocating members, one for each such crank pin of one said shaft and for the corresponding crank pin of the other shaft, 15 each such reciprocating member having sliding bearings for the bearing blocks of its corresponding crank pins, and two scavenging pumps for each such reciprocating member, the scavenging pumps for each such reciprocating member comprising two cylinders located on opposite sides of such reciprocating member, and each provided with a piston connected to 20 the corresponding reciprocating member to be reciprocated thereby.

5. An internal combustion engine comprising in combination two crank shafts mounted for rotation, cylinders and pistons 30 therefor, arranged to drive said crank shafts, said crank shafts each having, aside from the crank pins to which the pistons of said cylinders are connected, two other crank pins, angularly spaced apart, two members 35 mounted for reciprocation between said crank shafts and each having two transverse guides, and bearing blocks for the last mentioned crank pins of said crank shafts, each having a slide bearing on opposite sides of 40 a corresponding transverse guide of one of said reciprocating members.

6. An internal combustion engine comprising in combination two crank shafts mounted for rotation, cylinders and pistons 45 therefor, arranged to drive said crank shafts, said crank shafts each having, aside from the crank pins to which the pistons of said cylinders are connected, two other

crank pins, angularly spaced apart, two members mounted for reciprocation between 50 said crank shafts and each having two tubular transverse guides, bearing blocks for said last mentioned crank pins of said crank shafts, each having a sliding bearing on the exterior surface of a corresponding transverse guide of one of said reciprocating members, a guide member for each such bearing block working in the interior of a tubular transverse guide of the corresponding reciprocating member, and means connecting each such bearing block with its 55 said corresponding guide member.

7. An internal combustion engine comprising in combination two crank shafts mounted for rotation, cylinders and pistons 60 therefor, arranged to drive said crank shafts, and means for communicating motion from one crank shaft to the other, comprising a reciprocating member suitably guided and having cylindrical tubular transverse guides, 65 and transversely movable bearing blocks mounted to slide on said transverse guides and having shoes movable in the tubular portions thereof, the cranks of said crank shafts having bearings in said bearing 70 blocks.

8. An internal combustion engine comprising in combination two crank shafts mounted for rotation, cylinders and pistons 75 therefor, arranged to drive said crank shaft, 80 and means for communicating motion from one crank shaft to the other, comprising a hollow I-shaped member suitably guided and the transverse upper and lower members of which are of cylindrical bore, 85 and transversely movable bearing blocks mounted to slide on the said upper and lower members and having shoes movable in the cylindrical bores thereof, the cranks of said crank shafts having bearings in said bearing 90 blocks.

LEON WYGODSKY.
